US00D950649S

(12) **United States Design Patent** (10) **Patent No.:** **US D950,649 S**
(45) **Date of Patent:** **** May 3, 2022**

(54) **GAME BOARD**

(71) Applicant: **Dongguan XingZhan Electronic Technology Co., Ltd.**, Dongguan (CN)

(72) Inventor: **Guoxing Deng**, Zaoyang (CN)

(73) Assignee: **Dongguan XingZhan Electronic Technology Co., Ltd.**, Dongguan (CN)

(**) Term: **15 Years**

(21) Appl. No.: **29/797,685**

(22) Filed: **Jul. 1, 2021**

(51) LOC (13) Cl. **21-01**
